H. G. HOUGHTON,
RAILROAD TIE,
APPLICATION FILED JULY 20, 1915.

1,169,158.

Patented Jan. 25, 1916.

HORATIO G. HOUGHTON INVENTOR.

BY C. F. Bond

his ATTORNEY.

UNITED STATES PATENT OFFICE.

HORATIO G. HOUGHTON, OF GREEN BAY, WISCONSIN.

RAILROAD-TIE.

1,169,158.

Specification of Letters Patent. Patented Jan. 25, 1916.

Application filed July 20, 1915. Serial No. 40,914.

To all whom it may concern:

Be it known that I, HORATIO G. HOUGHTON, a citizen of the United States of America, residing at Green Bay, in the county of 5 Brown and State of Wisconsin, have invented certain new and useful Improvements in Railroad-Ties, of which the following is a specification, reference being had therein to the accompanying drawing.

- 10 This invention relates to improvements in railroad ties and has for its object the production of a practically indestructible tie provided with shock absorbing end block or rail beds.
- 15 A further object of my invention is to provide a tie with detachable shock absorbing ends, which ends may be quickly and readily detached and replaced without disturbing the tie proper and without making 20 it necessary to replace the entire tie.

Heretofore in railroad ties of this nature, which have been constructed throughout of concrete, molded in a variety of forms, the 25 rigidity and non-shock absorbing of the material used, causes the tie to crack which entirely destroys the tie, and in several instances caused disastrous results. By the use 30 of my improved tie, danger from this source is entirely eliminated, the end blocks being composed of a fibrous material preferably wood which serves as a bed for the rails and to which they are attached, are joined together by an interposed block of 35 some suitable adhesive material preferably concrete. It will be seen that by this arrangement, the wooden bed blocks will efficiently absorb the shocks without danger of cracking the interposed concrete tie.

With these and other objects in view, this 40 invention consist of certain novel combinations, constructions and arrangement of parts as will be hereinafter fully described and claimed.

In the accompanying drawings:—Figure 45 1 is a perspective view of my improved tie, showing the shock absorbing ends secured thereto. Fig. 2 is a perspective view of my improved tie with the shock absorbing ends removed. Fig. 3 is a perspective view of a 50 shock absorbing end piece or block which is adapted to fit to each end of the tie. Fig. 4 is a longitudinal, sectional view in elevation of my complete tie, showing the rails thereon.

55 Referring to the accompanying drawing, 1 represents the tie proper which is molded

preferably of concrete and square in section. At each end of this tie 1 are transverse slots 2, adapted to receive the transverse tongue 3 formed on the end of each of the bed blocks 60 4. These end bed blocks 4 are made preferably of wood which has been previously treated by the creosote process for preserving and are secured at each end of the tie 1 so as to form a bed for the rails. 65

A tie bolt 5 screw threaded at each end and adapted to pass through the centrally positioned longitudinal hole 6 in the tie 1 and end blocks 4 so as to securely tie and bind the said ends to the tie 1 when the nuts 70 7 are tightened, forming the combination in a substantial one piece construction.

The transverse tongues 3 prevents the end blocks 4 from moving out of alinement with the tie block 1, also relieving the tie bolt 5 of 75 considerable strain.

It will be seen that to renew the end blocks 4 while the tie is in place, the nuts 7 on the ends of the tie bolt 5 are removed, the blocks 4 may then be slid away from the tie 1 without disturbing the latter, new blocks can then be replaced thereon, the nuts 7 are again screwed on to the bolt 5 and screwed home.

From the foregoing description it will be seen that a very simple, cheap and durable 80 shock absorbing tie has been produced, and that the bed blocks can be quickly and cheaply renewed.

Various changes in the form, proportion and the minor details of construction may be 90 resorted to without departing from the principle or sacrificing any of the advantages of the invention as defined in the appended claims.

Having thus described my invention, 95 what I claim is:—

1. A tie of the class described, comprising a rectangular block composed of plastic material, shock absorbing means adapted to form a bed for rails secured at each end of the said rectangular block, and a tie bolt adapted to pass longitudinally through the said shock absorbing means and rectangular block for securely binding the said parts together. 100

2. A tie comprising a rectangular block composed of plastic material, shock absorbing rail beds composed of a fibrous material and adapted to be secured to each end of the said rectangular block and a tie bolt adapted 105 to pass centrally and longitudinally through the said shock absorbing blocks and rec-

tangular block for binding the said parts together.

3. A tie comprising a rectangular block composed of plastic material, transverse slots in the ends of said block, shock absorbing bed blocks composed of a fibrous material and provided with transverse tongues adapted to fit the slots in the ends of said rectangular block, and a tie bolt adapted to pass longitudinally through the said parts for securely binding them together.

4. A tie comprising a concrete rectangular block having transverse slots in the ends

thereof, wooden rail beds or blocks secured adjacent the ends of said concrete block, said wooden blocks provided with transverse tongues adapted to engage the said transverse slots for the purpose of holding the said wooden blocks in alinement therewith, and a tie bolt adapted to pass longitudinally through the said wooden blocks and concrete block for binding the same together.

In testimony whereof I hereunto affix my signature.

HORATIO G. HOUGHTON.
